STANISLAW SKIRTUN, OF SAN FRANCISCO, CALIFORNIA.

WAVE-MOTOR.

950,460.

Specification of Letters Patent. Patented Feb. 22, 1910.

Application filed October 5, 1909. Serial No. 521,040.

To all whom it may concern:

Be it known that I, STANISLAW SKIRTUN, a subject of Russia, residing at San Francisco, in the county of San Francisco and State of California, have invented new and useful Improvements in Wave-Motors, of which the following is a specification.

The present invention relates to an improved wave motor, the object of the invention being to provide an apparatus of this character which will utilize the force of the waves very efficiently and economically.

In the accompanying drawing, Figure 1 is a vertical sectional view of the apparatus; Fig. 2 is a cross section on the line 2—2 of Fig. 1; Fig. 3 is an enlarged vertical section of one of the air compressors.

Referring to the drawing, 1 indicates a well frame, having side walls 2 secured to 20 posts 3 driven into the bed of the ocean, open at the end opposite the ocean and closed at the shore end by a swinging gate 4 pivoted, as shown at 5 upon the frame. On the inner or opposing surfaces of said side walls 2 are formed vertical guides 6 for a float 7. Converging toward and meeting the ends of said walls at the open end of the well are walls 8, between which the waves, entering the wide end of the space between 25 the walls and traveling to the narrow end, greatly increase in height, so as to produce an increased effect upon the float upon entering the float well. To the top of the float are pivotally secured links 10, which are 30 connected at their upper ends to plungers 13, which reciprocate in vertical cylinders 14 supported upon the frame. In the upper end of each cylinder is an inlet check valve 15 and an outlet check valve 16. From the 35 outlet check valves flexible pipes 17 lead to a receiver 18 for compressed air. The end of the float at the open end of the well is contracted and curved upwardly, terminating in an edge as shown at 26, like the bow of a 40 punt, the object being to increase the lifting effect of the wave when it impinges upon said curved end. said cylinders having 45 guide ribs 27 which can slide vertically in guideways 28 secured upon the frame. The 50 cylinders may be adjusted to any desired position to conform to varying heights of the tide by means of screws 19 connected to said cylinders and screwed through bearings 20 on the frame. From said gate ex- 55 tends upwardly an arm 21 having a pin and slot connection 22 with a plunger rod 23 of a

plunger, which reciprocates in a cylinder 24 of the same construction as the vertical cylinders already described, and is in like manner connected to the air receiver.

The operation of the apparatus is as follows:—The wave entering the wide mouth formed by the two converging walls greatly increases in height as it travels to the float well. On arriving at the open end of the well it passes into the well and raises the float, operating the vertical air compressors and forcing air into the receiver. It then passes out of the well and in doing so forces back the gate 4 thereby operating the horizontal air compressor. When the wave has passed through the gate and the depression or trough in the water arrives at the well, the fall of the level of the water between the converging walls produces a greatly increased effect in that in the well itself, and this is further increase by the fact that the gate has shut, preventing return of the water which has passed therethrough. For this reason the float rises and falls through a much greater amplitude than the normal difference in level between the trough and the crest of the wave. The compressed air thus stored may be used for any desired purpose for which power is required.

I claim:

1. A wave motor comprising walls forming a well, open at one end, a swinging gate closing the other end of the well, walls converging toward said open end, a float in said well, and means for generating power from the rise and fall of the float in said well, substantially as described.

2. A wave motor comprising walls forming a well, open at one end, a swinging gate closing the other end of the well, walls converging toward said open end, a float in said well, means for generating power from the rise and fall of the float in said well, and means for generating power by the swinging of said gate, substantially as described.

3. A wave motor comprising walls forming a well, open at one end, a swinging gate closing the other end of the well, walls converging toward said open end, a float in said well, air compressor cylinders, plungers in said cylinders operatively connected to said float, a receiver for the compressed air, and connections from said cylinders to said receptacle, substantially as described.

4. A wave motor comprising walls forming a well, open at one end, a swinging gate

closing the other end of the well, walls converging toward said open end, a float in said well, air compressor cylinders, plungers in said cylinders operatively connected to said 5 float, means for varying the height of said cylinders, a receiver for the compressed air, and flexible connections from said cylinders to said receptacle, substantially as described.

5. A wave motor comprising walls forming a well, open at one end, a swinging gate closing the other end of the well, walls converging toward said open end, a float in said

well, said float having its end next to said converging walls contracted and curved upwardly, and means for generating power 15 from the rise and fall of the float in said well, substantially as described.

In testimony whereof I have hereunto set my hand in the presence of two subscribing witnesses.

STANISLAW SKIRTUN.
